ROPE DIE

Harold Cantrell, Thomas Jackson, and William Howarth, Spondon, near Derby, England, assignors to British Celanese Limited, London, England, a company of Great Britain

Application June 17, 1943, Serial No. 491,142
In Great Britain April 25, 1942

5 Claims. (Cl. 57—138)

This application is concerned with the manufacture of ropes, lines, cords and the like and is particularly concerned with the apparatus employed in such manufacture for the laying and closing of the strands of the rope.

In the practice of rope-making, the threads or strands of which the rope is made are passed through a throat or die mounted in the turning head of the machine, the throat or die being formed of a tapered bush flanged at one end for the purpose of axially locating the die and being fitted with a key or snug to ensure its rotation with the turning head. The length, diameter and taper of the throat or die depend upon the nature and size of the strand or rope being made and if a different size of rope is required it is necessary to replace the throat with another of the appropriate size. The provision of the necessary ranges of throats of different dimensions necessary to render a machine adaptable for the production of different sizes of rope is thus very costly and it is an object of the present invention to provide a form of throat or die which may be adjusted in length, taper and diameter without the necessity of keeping in stock a large number of throats or dies.

According to the present invention, a throat or die for use in the turning head of a rope-making machine comprises a series of plates each having a circular aperture therein and means for clamping said plates together so that said apertures are aligned with one another to form a tube. Preferably the edges of the apertures are rounded, so as to enable adjacent discs to be of different diameters without presenting a sharp edge to the material passing through the throat. By these means, with a suitable stock of apertured plates a throat or die of any desired length, diameter and taper may easily and quickly be built up, the stock of apertured plates necessary for the purpose being far smaller and less expensive than the range of throats or dies that can be made up from them.

A convenient method of clamping together the series of discs is by assembling the discs in a sleeve cut to the appropriate length and having an inwardly projecting flange at one end in order to retain the discs, and securing the discs at the other end of the sleeve by means of a cap, also provided with an inwardly projecting flange, screwed over the outside of the sleeve. The inwardly projecting flanges on the sleeve and the securing cap, particularly the flange at the input end of the throat, are preferably rounded off so as not to present a sharp edge, and in addition the discs at the ends of the series, particularly

5 that at the input end may be flared, or rounded to a greater extent on the side adjacent to the securing flange than on the other side. In this arrangement, the sleeve in which the discs are assembled may be relied on to hold the discs coaxially in register with one another. Any other suitable means, however, may be used for this purpose.

10 In addition to the adjustment of the length, diameter and taper of the tube constituting the throat, the invention makes possible variations in the general form of the tube, and in particular enables a tube to be made having a slight expansion at the output end instead of contracting continuously from the input to the output end. This expansion relieves abrasive action between the outlet end of the tube and the rope, which, in the course of the operation, remains stationary, while the head in which the throat is mounted rotates.

15 The invention is applicable to the manufacture of ropes, lines, cords and like products generally, whatever the material from which they are made but is of particular advantage in making such products from continuous filaments that have been stretched in the presence of a softening agent so as to impart to them a high tensile strength. Examples of materials that may be treated in this manner are the organic derivatives of cellulose, particularly cellulose acetate, 20 continuous filaments of which may be stretched to 5, 10 or more times their original length with a consequent increase in strength of up to 4.5 grams per denier or more. Where filaments of 25 cellulose ester are stretched in this manner for the purpose of being made into ropes, e. g., as described in Canadian application S. No. 483,499 filed June 10, 1941, they may be further improved by being subsequently saponified, which reduces their weight without reducing to a corresponding degree the tension they are able to withstand, so that their tensile strength in grams per denier is further increased, e. g., up to 6 grams per denier or more. The use of a throat or die having 30 a slightly tapered outlet is of especial advantage in connection with materials of this kind since the stretched continuous filaments are often extremely fine and are more liable to damage by abrasion than coarser fibres such as the natural fibres commonly used in the manufacture of ropes.

35 The ready adjustment, at will, of the dimensions and form of the throat that is obtainable by the present invention has far reaching effects 40 on the optimum conditions for the manufacture of ropes, lines, cords and like products. For ex-

ample, it makes it economically profitable to pay greater attention than heretofore to the precise control of the tension in the material during the laying and closing operation, so that a product may be obtained that is more even both along its length and as between the different fibres in its cross-section. Again, by a suitable selection of throat dimensions and tension conditions it is possible to obtain ropes which, while of great uniformity and stability, are of less density, i. e., of greater bulk per unit of weight. This feature, in combination with the use of artificial materials of exceptional tensile strength as noted above, enables ropes of natural fibres to be matched, as to both strength and diameter, by ropes which are nevertheless lighter in weight. Ordinarily, the use of stronger materials would enable only the strength or the diameter to be matched, a thinner and lighter rope resulting in the first case and an unnecessarily strong and heavy rope in the second case. It appears possible that this result of the present invention, of enabling satisfactory ropes of lower density to be obtained, may be assisted by the ridged character of the internal surface of the throat or die. This arises from the rounded form of the edge of the aperture in each disc, the primary purpose of which is to enable transition from a larger to a slightly smaller aperture to take place without presenting a sharp edge with which the material in the rope is likely to come in contact inside the die or throat. The ridged nature of the internal surface of the throat causes the pressure applied to the rope by the throat for the purpose of compacting and closing the strands of the rope to be applied intermittently instead of continuously, so that the average action on the rope for a given maximum compacting pressure is of a gentler character than where a smoothly tapered bore is employed.

By way of example one form of throat or die in accordance with the present invention will now be described in greater detail with reference to the accompanying drawing, which shows the throat or die in sectional side elevation.

The throat is built up from a series of 15 discs 1, each of a thickness of $\frac{1}{4}$ " and of an external diameter of 1". Each disc has a central perforation ranging in the different discs from $\frac{1}{2}$ " on the right hand side of the figure to $\frac{5}{16}$ " in the disc particularly indicated at 2. The edge of the aperture in each case is rounded to a radius of $\frac{3}{16}$ ". The internal diameters of the adjacent discs 1 differ from one another by $\frac{1}{64}$ " so that the throat gradually tapers from $\frac{1}{2}$ " at the wide or inlet end (at the right hand side of the figure) to $\frac{5}{16}$ " at the thirteenth disc indicated at 2, the remaining two discs 3 and 4 increasing again by similar steps so that the outlet or left hand end of the throat is slightly divergent for a short distance.

The discs 1 to 4 are packed together in a sleeve 5 having an internal flange 6 and an external flange 7 at the inlet end. The internal flange 6 is adapted to retain the discs 1 and is rounded at 8 on the inlet side of the flange to a radius of $\frac{1}{4}$ ". The aperture of the disc 1 adjacent to the flange 6 is rounded about a centre slightly offset from the middle of the disc's thickness so that the edge of the aperture is more rounded on the inlet side (next to the flange 6) than on the other. The external flange 7 serves to locate the throat axially in the turning head in which it is used. A pin 9 is mounted in the external flange to engage with a slot in the turning head

so as to ensure that the throat rotates with the turning head.

The other end of the sleeve 5 is externally screw-threaded and over it is screwed a cap 10 having an internal flange 11 which engages the disc 4 at the outlet end of the throat and retains all the discs. The sleeve 5 is cut to a length of just under $3\frac{3}{4}$ " so that the last disc 4, at the outlet end of the throat just fits into the sleeve 5 and is engaged by the internal flange 11 of the retaining cap 10.

Having described our invention what we desire to claim by Letters Patent is:

1. A throat or die for rope-making comprising a series of plates each having an aperture therein and means for clamping said plates together so that said apertures are aligned with one another to form a tube, the edge of each of said apertures being rounded so that its intersection with any plane through the axis of said tube is wholly convex towards said axis.

2. A throat or die for rope-making comprising a series of plates each having a circular aperture therein, each of said apertures having a rounded edge, and means for clamping said plates together so that said apertures are aligned with one another to form a tube, said apertures being arranged so as to decrease in diameter from one end of said tube to a point near the other end and to increase again from said point to said other end.

3. A throat or die for rope-making comprising a series of plates each having a circular aperture therein, each of said apertures having a rounded edge, a sleeve adapted to hold said plates in alignment with one another so that they form a tube, an internal flange at one end of said sleeve for retaining said plates therein and a cap having an internal flange and adapted to be secured to the other end of said sleeve so as to clamp said plates, said plates being so arranged that the apertures therein decrease in diameter from the inlet end of said tube to a point near the other end and increase again from said point to said other end, the edge of the aperture at the inlet end of the tube being more rounded on the inlet side of the plate than on the other side.

4. A throat or die for rope-making comprising a series of plates each having an aperture therein, a sleeve adapted to hold said plates in alignment with one another so that they form a tube, the edge of each of said apertures being rounded so that its intersection with any plane through the axis of said tube is wholly convex towards said axis, an internal flange at one end of said sleeve for retaining said plates therein and a cap having an internal flange and adapted to be secured to the other end of said sleeve so as to clamp said plates.

5. A throat or die for rope-making comprising a series of plates each having an aperture therein and means for clamping said plates together so that said apertures are aligned with one another to form a tube, the edge of each of said apertures being rounded so that its intersection with any plane through the axis of said tube is wholly convex towards said axis, the edge of the aperture at the inlet end of said tube being more rounded on the inlet side of the plate than on the other side.
